CLAIM

The ornamental design for a floodlight fixture, as shown and described.

DESCRIPTION

FIG. 1 is a perspective view of a floodlight fixture showing the present invention;

FIG. 2 is a front elevation of FIG. 1;

FIG. 3 is a back elevation of FIG. 1;

FIG. 4 is a top plan view of FIG. 1;

FIG. 5 is a bottom plan view of FIG. 1;

FIG. 6 is a right side elevation of FIG. 1; and,

FIG. 7 is a left side elevation of FIG. 1.

The broken lines in the drawings illustrate portions of the floodlight fixture that form no part of the claimed design.
